HEEL BRACE

Harry James Hagan, Roanoke, Va.

Application April 18, 1932. Serial No. 606,052

2 Claims. (Cl. 36—76)

This invention relates to braces for shoe heels and more particularly for the heels of ladies' shoes.

In accordance with the present invention a brace of the character above mentioned is provided which is extremely simple in construction, may be readily and easily applied to the shoe, and will efficiently brace and reinforce the heel.

10 The invention together with its numerous advantages will be best understood from a study of the following description, taken in connection with the accompanying drawing wherein:

Figure 1 is a perspective view of one form of brace, the same being shown applied to a shoe.

Figure 2 is a sectional elevational view through the brace and portion of the shoe.

Figure 3 is a perspective view of a slightly modified form of the brace.

20 In accordance with the present invention the heel brace is preferably formed from a single blank of metal or other suitable material and comprises a main plate like body portion 5 provided with strengthening ribs 6 elongated longitudinally, and a heel portion 7 extending downwardly from the portion 5 and having an opening 8, resulting in the application of the brace, in a tongue 9 that it tapers toward its free end and continues longitudinally from the plate portion 5. At the junction of the portions 5 and 7 the brace on the under side thereof is provided with corrugations or strengthening ribs 10.

As shown in Figures 1 and 2, the plate 5 is provided with apertures 11 whereby the portion 5 of the brace is secured to the under side of the sole of the shoe 12, at the instep and in proximity to the shoe heel 12a. The downturned part 7 of the brace engages the inner face of the shoe heel 12a and is secured thereto as at 13. The tongue 9 is seated on the seat of the heel 12a, and when the brace is thus applied to the shoe it will be seen that the heel 12a will be secured against inward deflection and against possibly breaking off from the shoe.

In the form of the invention shown in Figure 3, it will be seen that said form is similar to that shown in Figures 1 and 2 and described above with the exception that instead of the downturned portion 7 the plate like body portion 5' on opposite sides of the tongue 9' is provided with downturned lugs 7' reinforced by strengthening ribs 10'; and when the brace shown in Figure 3 is applied to the shoe, it will be apparent that parts 5' and 9' will engage the shoe

sole and shoe heel respectively as the parts 5 and 9 of the first form of the invention while the downturned lugs 7' will bear against the inner face of the shoe heel immediately adjacent the upper end or seat end of the heel. 60

Even though I have herein shown and described the preferred embodiments of my invention it is to be understood that I am fully aware that further changes may be made therein, and accordingly claim all such forms of the invention 65 to which I am entitled in view of the requirements of the prior art and scope of the appended claims.

Having thus described my invention, what I claim as new is:

1. As a new article of manufacture, a shoe heel brace comprising a plate having a substantially rectangular end portion and a tapered end portion, the lateral edges of which merge into a point at the extremity of the plate; the rectangular end portion having spaced longitudinal ribs pressed therefrom whereby said end portion is laterally contracted and reduced in width beyond the normal width of the plate; said plate at the widest portion thereof being also provided 80 adjacent its side edges with short longitudinal slits and bent to provide lugs projecting at right angles from the plate at opposite sides of the tapered end thereof; and strengthening ribs for the lugs struck out from the widest portion of 85 the plate in substantial alignment with the first named ribs. 75

2. As a new article of manufacture, a shoe heel brace comprising a plate having a laterally contracted substantially rectangular end portion, 90 an intermediate portion of a width corresponding to the normal width of the plate, and a laterally reduced tapered end portion terminating in a penetrating point; said plate having its intermediate portion provided with short longitudinal slits in substantial alignment with the respective lateral edges of the tapered end of the plate; and bent on transverse fold lines at the inner ends of the slit to provide depending relatively short lugs. 95
